CLAIM

I claim the ornamental design for a cordless shrub shear, as shown and described.

DESCRIPTION

FIG. 1 is a top view of the cordless shrub shear showing my new design;

FIG. 2 is a left side elevation view thereof;

FIG. 3 is a right side elevation view thereof;

FIG. 4 is a right rear perspective thereof;

FIG. 5 is a left front perspective thereof;

FIG. 6 is a left front perspective thereof;

FIG. 7 is a rear view thereof;

FIG. 8 is a bottom view thereof; and,

FIG. 9 is a front view thereof.

The broken lines depict portions of the cordless shrub shear that form no part of the claimed design.
